UNITED STATES PATENT OFFICE.

ISIDOR KITSEE, HENRY ILLOWAY, AND PETER A. KECK, OF CINCINNATI,
OHIO, ASSIGNORS TO THE PARLOR CATTLE CAR COMPANY, OF SAME
PLACE.

STOCK-CAR.

SPECIFICATION forming part of Letters Patent No. 241,378, dated May 10, 1881.

Application filed March 8, 1881. (No model.)

To all whom it may concern:

Be it known that we, ISIDOR KITSEE, HENRY ILLOWAY, and PETER A. KECK, of Cincinnati, Hamilton county, Ohio, have invented certain new and useful Improvements in Stock-Cars, of which the following is a specification.

This invention relates to that class of stock-cars in which the body of the car is divided into separate compartments or stalls for the animals.

Its object is to provide strong durable stall-sides which will effectually separate and support the animals when standing, and will not interfere with the loading and unloading, or the comfort of the animals when lying down. This object is accomplished by the means illustrated in the accompanying drawings, in which—

Figure 1 is a horizontal section of a portion of a car embodying our improvements. Figs. 2, 3, and 4 are side elevations of different forms 20 of stall-sides secured to the floor of the car. Fig. 5 is an enlarged view of the feed and water troughs, and the rail of the door to which they are secured. Fig. 6 is a greatly-enlarged longitudinal section view of the telescopic pipe-joints by which the water-troughs upon the different doors are coupled together when car is loaded and closed up. Fig. 7 is a side elevation of our preferred form of stall-side, showing also, in transverse section, the framing-timbers 25 and floor of the car; and Fig. 8 is a top-plan view of a portion of one side of a car with our improved stall-sides arranged diagonally therein.

The body of the car is constructed in the usual way, except the upright stiles, which are 30 grooved to receive vertically-sliding bar-doors A. Secured upon bar A are the water-troughs B and feed-troughs C. The water-troughs are triangular in shape, and are placed in the acute angle at the head of the stalls. They are made 35 to incline from the top front edge toward the lower inner angle, so that the horns of the cattle are not liable to strike the bottom of the trough in getting up. The feed-trough C is placed within, and slightly above, the water-trough, as 40 shown in Figs. 1 and 5, but may, if desired, be placed in the opposite angle, or alongside of the water-trough.

In Fig. 2, D is an inclined bar, one end of which is secured to the car-floor, and the opposite site end secured to an upright stile of the car.

body; and E is a metal brace secured to the bar D and the car-floor.

In Fig. 3 is shown a triangular board, which forms the stall-side. This is secured to the floor and to the upright framing of the car in any 55 approved manner.

In providing a car with the form of stall-sides shown in either Fig. 2 or Fig. 3, the series of stalls arranged upon each side of the car should have their sides arranged alternately with the 60 high end of the sides in opposite directions, so that the animals, in entering the stalls or in lying down, may, by inclining their heads to one side, avoid striking their horns. In the form shown in Fig. 4 the side consists of two bars, F, joined to the floor at each end of the stall, their opposite ends inclining up, joined opposite the longitudinal center of the stall, and supported by an upright brace, G.

Our preferred form of stalls (illustrated in 70 Figs. 7 and 8) are each formed of two pieces, H, framed together at the top by a cross-piece, I. The pieces H have a bend at the lower ends, to pass vertically down through the car-floor and rest against the longitudinal timbers J of 75 the car, to which they are secured firmly by metal angle-pieces K, and bolts which secure the angle-pieces to the timbers and pieces H. These stall-sides do not extend to either the side of the car or to the partition which longitudinally divides the car-body, so that when 80 the central partition is elevated the cattle may pass between the two rows of stalls in loading the cars.

We also design to use our cars without a 85 central dividing-partition. In this case the animals will be secured in their stalls by head-chains secured to the sides of the car.

The water-troughs in the different stalls are connected together by pipes L and sliding joint 90 M. When the side doors are closed the joint-pipe M is slipped over the ends of the pipes L of the adjacent troughs, as seen in Fig. 6, so that all the troughs upon one side of the car may be supplied with water at the same time. 95

With our stall-sides it is not necessary that the sides of the car be furnished with vertically-sliding doors. The car may be framed up rigidly upon the sides, and have one door at each end for loading and unloading the stock. 100

In this case, of course, the joint M of the water-pipe will not be necessary.

It will be seen that as our improved form of stall-sides are secured below and the upper end free they will, while being strong enough to support the animals, at the same time have sufficient spring to give slightly, in case the animals are jarred against them by the starting or checking up of the train, and thus avoid bruising the animals. We find it best to make the side pieces, H, of hard springy timber, and about six inches wide by two inches thick, with the corners slightly rounded.

We have shown the stall-sides inclined from the floor toward the center of the stall-side, and this we think the best form, as it leaves more room for loading and unloading, and more room for the animals in lying down; but if the pieces H were straight and placed vertically good results would be produced, especially if the ends by which they are secured be placed nearer together.

It would not vary the principle of our invention to omit the metal angle-pieces K, and bolt or otherwise secure the pieces H to the timbers J.

We claim—

1. The combination, substantially as herein-before set forth, of a stock-car and a series of stalls arranged therein, the sides of said stalls being secured to the floor or lower timbers of the car-body, and so placed as to brace and support the animals near the center of their bodies when standing, and one or both ends of each pair of sides sloping down to near the floor of the car at the head of the stall, for the purpose set forth. 30

2. In a stock-car, the combination, substantially as specified, of the lower timbers, J J, with the stall-sides formed of side pieces, H H, and top cross-piece, I, said pieces being framed together and secured to said timbers. 40

3. The combination, substantially as herein-before set forth, of the car-body and a series of stalls arranged therein, the stall-sides formed of the pieces H H I, framed together at the top, and secured to the lower timbers of the car-body by angle-pieces K. 45
